UNITED STATES PATENT OFFICE

CARL T. MADSEN, OF OAK PARK, ILLINOIS, ASSIGNOR TO CHICAGO FLEXIBLE SHAFT COMPANY, OF CHICAGO, ILLINOIS, A CORPORATION OF ILLINOIS

HANDLE FOR LAUNDRY IRONS

Application filed March 19, 1927. Serial No. 176,596.

The purpose of this invention is to provide a handle for a laundry iron and like implement with a hand piece which shall be prevented from excessive heating by conduction from the hot body of the iron by means of automatically produced air circulation through such hand piece. It consists in the elements and features of construction shown and described as indicated in the claims.

10 In the drawings:—

Figure 1 is a vertical section longitudinal with respect to the handle of a laundry iron handle embodying the invention, the body of the iron being shown in dotted line.

15 Figure 2 is an end elevation of the same.

Figure 3 is a detail section at line 3—3 on Figure 2.

Figure 4 is a section similar to Figure 1, showing a modified form.

20 Figure 5 is an end elevation of the form shown in Figure 4.

Figure 6 is a view similar to Figure 1 showing a third modification.

25 Figure 7 is an end elevation of the form shown in Figure 6.

Figure 8 is a view similar to Figure 1 showing a fourth modification.

Figure 9 is an end elevation of the form shown in Figure 8.

30 In all the forms of the invention illustrated in the drawings the body of the iron is indicated in dotted line at A, and the hand piece at B. The standards are preferably in one piece of metal bar folded in U-form with

35 its upstanding ends constituting the two standards, and this bar is indicated throughout the drawings by the reference letter C. In all forms the hand piece, B, is of material

having a low coefficient of thermal conductivity, such as wood, indurated fiber, or well-known refractory compositions having that thermal characteristic, and is tubular, that is,

40 having a hollow cavity extending longitudinally from end to end, and in the forms

45 shown in Figures 1 to 7 it is recessed at the ends around the longitudinal cavity, or rabbeted, as seen at 10—10, forming shoulders, 11—11.

The marginal flanges, 12—12, at the ends of the hand piece each have a notch, 13, 50 both said notches being at the same side of

the hand piece and in alignment with each other for accommodating the standards which extend up from the body of the iron and are formed at their upper ends for entering the rabbet-shoulder-forming recesses 55 at the ends of the hand piece. The upturned ends of the bar, C, constituting the standards are designated by reference letters, C¹, C², C³ and C⁴ in the respective forms illustrated, and in Figures 1 to 5 and 8 and 9 they have their upper ends fitted as described above in the recesses, 10—10, and at the center of their arcuate ends they have an aperture, 14, for a tie bolt, 20, which extends through the longitudinal cavity of the hand piece. This tie bolt 60

may be in the form shown in Figure 1 having a head, 21, abutting at one end against the outside of a support, C¹, and exteriorly threaded at the other end, beyond the other support C¹ to receive a nut, 22. In the form 65

shown in Figure 4, the standard through which the threaded end of the bolt extends may have its aperture, 14, threaded, and the tie bolt may be screwed into it protruding at 70

the outside to receive a jam nut, 23, the head of the bolt in that case being preferably slotted for screwing it into the standard as described. In the modified form shown in 75

Figure 8 the tie bolt is without a head and is similarly threaded at both ends and dimensioned for protruding the threaded ends through the apertures, 14, of the standards, C⁴, for receiving nuts, 23, outside the standards respectively. In either of the forms described 80

the tie bolt is hollow from end to end and constitutes an air duct through which a current of air is caused to pass by the back-and-forth movement of the iron in ironing.

The rabbets forming the recesses, 10—10, are deep enough to cause the encompassing flange, 12—12, to extend completely over the ends of the tie bolt and the securing nuts, so that the hand of the operator is guarded from accidental contact with the upper end edges of the standards or with the head or nut of the tie bolt, these metal parts being liable to be hot enough to burn the hand if touched. Beside the ventilation provided by the hollow tie bolt it will be recognized that except in the forms shown in Figures 4 and 6 the tubu- 100

lar cavity of the hand piece provides a very substantially dimensioned insulation between the tie bolt and the inner surface of the hand piece; and to render this space not only effective for insulation by virtue of the air in it, but also effective for ventilation or air circulation through it, and as shown in Figure 1 it is rendered open at the ends by forming in the ends of the standards C^1 , which are seated in the end recesses, 10, of the hand piece arcuate apertures, 25—25, between the margins of said seated ends which obtain seating on the rabbet shoulders, 11—11, and the annular area around the bolt aperture necessarily reserved for stopping the bolt head or nut and carrying the thread with which the bolt engages in the form shown in Figure 1. It will be observed that the apertures, 25, 25, are so located as to be in registration with the annular cavity around the bolt. There are thus provided two through-and-through air circulation paths for carrying off the heat which may be radiated from the tie bolt or conducted to the hand piece by the limited contact of the standards, C^1 , C^1 , with the rabbet shoulders, 12—12.

A third air channel is provided in the form shown in Figure 1 by interposing a spacing tube, 30, between the ends of the standards, C^1 , C^1 , around the tie bolt, 20, said tube being exteriorly dimensioned enough less than the inner diameter of the hand piece, and interiorly dimensioned enough more than the outer diameter of the hollow bolt, to leave an annular air space around the bolt and around the spacing tube, as is indicated at 41 and 42 respectively. The spacing tube is desirably dimensioned longitudinally to agree with the distance between the rabbet shoulders, 11—11, at the opposite ends of the hand piece, so that the tie bolt drawn tightly will clamp the ends of the standards, C^1 , C^1 , simultaneously against the said rabbet shoulders, 11, and against the ends of the spacing tube, 30, the latter thus serving to relieve the shoulders of the hand piece of the severe stress which would be liable to deteriorate the non-metallic material of which the hand piece is necessarily formed, and prevent the looseness which would be liable to result from that deterioration after limited use.

In order that the annular air space, 42, may serve not only for air insulation but also and especially as an additional path for air circulation, the arcuate ends of the standards, C^1 , are formed with arcuate apertures, 27, 27, registering with the ends of said annular air space, 42.

In the form shown in Figure 4 the tubular spacer is dispensed with, and the hollow tie bolt is made somewhat greater in diameter than the form shown in Figure 1, substantially occupying the tubular cavity of the hand piece. The bar, C, whose upturned

ends form the standards, C^2 , C^2 , in Figure 4, is stiff enough to dispense with any means of spacing the ends of the supports apart for relieving the material of the hand piece of the clamping pressure due to tightening the nuts on the tie bolt; and the hand piece is dimensioned between the rabbet shoulders, 11—11, for snug fit between the ends of the standards, C^2 — C^2 . This may be regarded as the simplest form of the invention which is characterized in all its forms by the tie bolt and a ventilating passage throughout the length of the hand piece.

In Figure 6 there is shown a form of the invention which dispenses with both the tie bolt and the spacing tube, utilizing the entire unobstructed longitudinal cavity of the hand piece for air circulation. In this form the stiffness of the standards C^3 is relied upon to defeat their spreading apart so as to release the hand piece; and the engagement of the hand piece against vertical displacement for disengagement from the standards is afforded by making the notches, 13, less in width than the diameter of the recesses, 10, and forming the standards with their upper arcuate ends with diameter correspondingly greater than the width of the standard at the point at which they stand in the notches, 13. When made in this form, since the standards are too stiff to be sprung apart for entering the enlarged arcuate-heads of the standards in the recessed ends of the hand piece, the standards are preferably formed of separate pieces and separately secured upon the body of the iron as seen in Figure 6. The upper or arcuate ends of the standards are provided with apertures, 14^a, of substantially the same size and outline as the cross sectional area of the cavity, and positioned for registration therewith; thus forming a continuous unobstructed passage for air circulation through the hand piece.

For limiting as closely as possible the conduction of heat from the body of the iron through the standards to the hand piece, the area of contact of the bar, C, of which the standards are formed with the body of the iron, is reduced by flexing that bar upwardly out of contact with the body of the iron as seen at C^3 between the points of its securement to the body of the iron by the bolts, 15, as seen in Figures 1 to 5 and 8 and 9. And for further limiting the conduction of the heat which may be communicated even by the limited contact with the body of the iron, the standards at their upright extent are apertured as indicated at 16, 16 and 17, reducing them to a somewhat skeleton form. These apertures, besides reducing the cross section of the standards for limiting the conduction of heat by them to the hand piece, serve the further purpose of permitting air currents to be directed through them under the hand piece and past the hand of the oper-

ator grasping the latter, with substantial cooling value both by diverting the normally ascending current of hot air from the body of the iron, and by facilitating direct radiation from the hand of the operator.

In Figure 8 there is shown another modification consisting in forming the standards indicated in this form by the reference letter, C⁴, with shoulders, 18 stopping against the margins of the notches, 13, in the flanges, 12, of the hand piece, and locating the apertures for receiving the ends of the tie bolt at a distance from the shoulders corresponding approximately to the thickness of the wall of the hollow hand piece, so that the tie bolt extending through the hand piece is lodged against the inner wall of the latter at the lower side, causing the hand piece to be positioned and fixed in position between said shoulders, 18, at the outside and the tie bolt at the inside. In this form it is of minor importance that the tie bolt is hollow (though it is so shown in Figure 8), because of the longitudinal cavity of the hand piece being so slightly obstructed at its ends by the ends of the standards, that the air circulation through the hand piece is adequate for the desired cooling without the additional cooling of the tie bolt which results from the hollow character of the latter.

It will be observed that the characteristic common to all the forms illustrated, resides in the provision of a hand piece having a tubular cavity therethrough, either in the hand piece proper, or by means of a hollow bolt or tube, with the hand piece embraced endwise between a pair of spaced apart upright standards, which are provided with apertures located for registration or alignment with the ends of the cavity to provide a continuous passageway from end to end of the hand piece for circulation of air therethrough.

I claim:—

1. A laundry iron handle comprising a tubular handpiece and standards adapted to be secured to the body and extending upwardly from the body terminating with their upper ends spaced apart to admit and embrace the handpiece endwise between them; a tubular spacing member of exterior diameter less than the interior diameter of the handpiece extending longitudinally through the handpiece annularly spaced therefrom, and a tie bolt of less diameter than the cavity of the spacing member extending through the cavity of said spacing member and protruding therefrom and from the handpiece at opposite ends for receiving means for clamping the standards against the opposite ends of the spacing member.

2. A laundry iron handle comprising a tubular handpiece with its tube cavity extending through it from end to end and standards adapted to be secured to the body

of the iron and extending upwardly therefrom and terminating with their upper ends formed and spaced apart to admit and embrace the handpiece endwise between them, a tubular spacing member extending through the cavity of the handpiece in spaced apart relation forming an annular cavity thereabout, and a tie bolt extending through the tubular spacing member, and means on the handpiece-engaged ends of the standards positioning the spacing member and the tie bolt out of contact with each other and the spacing member out of contact with the handpiece, the standards having apertures positioned for registering with the annular space between the tie bolt and the tubular spacing member at opposite ends of the latter respectively.

3. A laundry iron handle comprising a tubular handpiece and standards adapted to be secured to the body and extending upwardly from the body terminating with their upper ends spaced apart to admit and embrace the handpiece endwise between them; a tubular spacing member of exterior diameter less than the interior diameter of the handpiece extending longitudinally through the handpiece annularly spaced therefrom, and a tie bolt of less diameter than the cavity of the spacing member extending through the cavity of said spacing member and protruding therefrom and from the handpiece at opposite ends for receiving means for clamping the standards against the opposite ends of the spacing member, the standards having apertures at their handpiece-embracing portions positioned for registering with the annular space outside the tubular spacing member.

4. A laundry iron handle comprising a tubular handpiece with its tube cavity extending through it from end to end; standards secured to the body of the iron and extending upwardly from the body terminating with their upper ends formed and spaced apart to admit and embrace the handpiece endwise between them, said standards having at their handpiece-embracing parts, apertures registering with the ends of said tube cavity of the handpiece; a tubular spacing member extending through the cavity of the handpiece in spaced apart relation forming an annular cavity about said spacing member, and a tie bolt extending through the spacing member, and means on the handpiece-engaged ends of the standards positioning the spacing member and bolt out of contact with each other and the tubular member out of contact with the handpiece.

In testimony whereof, I have hereunto set my hand at Chicago, Illinois, this 16th day of March, 1927.

CARL T. MADSEN.
